CLAIM

We claim the ornamental design for a tablet PC, as shown and described.

DESCRIPTION

FIG. 1 is a front perspective view of a tablet PC showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof.

FIG. 9 is an enlarged view of the encircled portion in FIG. 1; and,

FIG. 10 is an enlarged view of the encircled portion in FIG. 2.

The broken lines in the drawings represent portions of the tablet PC that form no part of the claimed design.

The dot-dot-dash broken lines in FIGS. 1, 2, 9 and 10 are included to show a partially enlarged view only and form no part of the claimed design.
